DESIGN FOR A MERCHANTISE DISPLAY RACK

Albert H. Newman, Chicago, Ill.

Application February 14, 1934, Serial No. 50,720

Term of patent 7 years

To all whom it may concern:

Be it known that I, ALBERT H. NEWMAN, a citizen of the United States, and a resident of Chicago, in the county of Cook and State of Illinois, have invented a new, original, and ornamental Design for a Merchandise Display Rack, of which the following is a specification, reference being had to the accompanying drawing forming a part thereof, wherein Fig. 1 is a perspective view of a merchandise display rack embodying the design and Figs. 2 and 3 are, respectively, a front elevation and a side elevation of the same.

I claim:

The ornamental design for a merchandise display rack as shown and described.

ALBERT H. NEWMAN.
